ATTORNEY

UNITED STATES PATENT OFFICE.

WILLIAM A. KEYS AND JARED LOCKWOOD, OF NEW YORK, N. Y.

BUCKLE.

SPECIFICATION forming part of Letters Patent No. 296,182, dated April 1, 1884.

Application filed November 2, 1883. (No model.)

To all whom it may concern:

Be it known that we, WILLIAM A. KEYS and JARED LOCKWOOD, of the city, county, and State of New York, have invented a new and useful Improvement in Buckles; and we do hereby declare the following to be a full, clear, and exact description of the same, reference being had to the accompanying sheet of drawings, forming part of this specification.

10 This invention is in the nature of an improvement in buckles; and the invention consists in a buckle combined with a device whereby the buckle may be disengaged from the fabric which is held by it, substantially as is 15 hereinafter more particularly shown, described, and claimed.

In the accompanying sheet of drawings, Figure 1 is a plan or top view of our improvement applied to a lever-buckle. Fig. 2 is a 20 longitudinal section of same on line *x x*. Fig. 3 is a top plan view of our invention applied to a prong-buckle, and Fig. 4 a longitudinal section of same on line *y y*. Fig. 5 is a top plan view of a modification, and Fig. 6 a longitudinal section of same, on line *z z*.

Similar letters of reference indicate like parts in the several figures.

This invention is designed to obviate the difficulty so well known of disengaging a buckle 30 from the fabric in which it is employed, particularly when the buckle is applied to neckties, scarfs, and the like neck-wear where the buckle engages with soft silks and satins. In such applications of the buckle, and when the 35 scarf is around the neck of the wearer, it is exceedingly difficult to disengage it from the strap of the scarf. Now, for the purpose of facilitating the disengagement of the buckle, we provide it with a lifting-piece projecting above 40 the plane of the tongue or prongs, to be readily engaged by the fingers or thumb, and arranged

between the points of the tongue or prongs and the pivot or pivots of the same. In Figs. 1 and 2 this lifting-piece A is a tongue of metal separated on three sides and raised from the 45 body of the metal of the lever *b*, between its points *a a* and its fulcrum.

In Figs. 3 and 4 the ordinary prong-buckle is provided with a bridge-piece attached to its prongs, between their points and pivots, and 50 having an upturned edge, as shown.

In Figs. 5 and 6 the lifting-piece is made as upward bends of the prongs between their points and pivots, as shown. By a backward and upward pressure on this lifting-piece A, in 55 either form shown, the points *a a* of the buckle are readily disengaged from the strap without loss of time and very expeditiously.

We are aware that lever-buckles have heretofore been made with a thumb-piece extending rearwardly of the fulcrum, for lifting the prong or pin out of a hole made in a leather strap to receive it; and we are also aware that a sheet-metal lever-buckle has had a lifting projection, or two of them, arranged in advance 65 of the pin or point; and such constructions form no part of our invention; but

What we claim is—

1. A buckle for use in textile fabrics, having a pivoted tongue provided with points *a* 70 and the lifting-piece A, projecting above the plane of the tongue and arranged between the points and pivot of the tongue, substantially as shown and described.

2. The combination, with the prongs of a 75 buckle, of the attached lifting-piece A, substantially as shown and described.

WILLIAM A. KEYS.
JARED LOCKWOOD.
